Des. 241,326
Patented Sept. 7, 1976

241,326

SAILBOAT

William I. B. Crealock, 1401 Forest Ave.,
Carlsbad, Calif. 92008

Filed June 23, 1975, Ser. No. 589,691

Term of patent 14 years

Int. Cl. D12—06

U.S. Cl. D12—64

FIG. 1

FIG. 2

FIG. 1 is a side elevational view of the starboard side of a sailboat. The port side is substantially identical in appearance to the starboard side. The mizzen sail may be optionally omitted.

FIG. 2 is a top plan view of the sailboat.

FIG. 3 is an elevational view from the bow.

FIG. 4 is an elevational view from the stern.

FIG. 5 is a composite of hull half sections taken at the respective stations of FIG. 1 in accordance with conventional practice.

FIGS. 2, 3 and 4 are shown with the mast, boom, sails, standing and running rigging omitted for convenience of illustration.

FIG. 5

FIG. 4

FIG. 3

The partial disclosure of surface texture of FIG. 2 is representative of the complete appearance within the borders shown.

What is claimed is:

The ornamental design for a sailboat, substantially as shown and described.
